FREDRIK LJUNGSTRÖM, OF BREVIK, LIDINGÖN, SWEDEN, ASSIGNEE TO AKTIEBOLAGET LJUNGSTRÖMS ANGTURBIN, A CORPORATION OF SWEDEN.

ELASTIC-FLUID TURBINE.

1,322,030.

Specification of Letters Patent. Patented Nov. 18, 1919

Application filed March 25, 1919. Serial No. 225,081.

To all whom it may concern:

Be it known that I, FREDRIK LJUNGSTRÖM, a resident of Brevik, Lidingön, in the Kingdom of Sweden, have invented certain new and useful Improvements in Elastic-Fluid Turbines, of which the following is a specification.

The present invention relates to elastic fluid turbines and specifically to that type having a radial flow high pressure blade system, the parts of which revolve in opposite directions, and also an axial flow low pressure blade system, the latter receiving steam from the former. In such a turbine the blades for the radial flow system are mounted on rotating elements and extend axially. The blades for the axial flow system are mounted on separate rotor elements which are attached to the inner elements and extend radially. The latter elements may and preferably do carry some of the axially extending intermediate pressure blades. For convenience of description the portions of the rotating structures carrying the radial blades will be referred to as wheels.

For certain important engineering reasons, which are not material to the present case, the wheels are made of separate structures and are connected to the inner portions by expansion rings through which torque is transmitted. Since the portions of the rotating elements which carry the radial flow blades also form the side walls of the radial flow portions of the steam space they must be relatively close together at some point gradually diverging as the volume of steam increases. As the volume of steam in the low pressure end of the machine is very large the last few rows of the radial flow blade, usually referred to as intermediate pressure blades, have to be pretty long and for that reason they are mounted on the wheels. Owing to the still greater volume of steam on the exhaust side of the radial flow blades the wheels with their radially disposed blades must be spaced a considerable distance apart.

In a turbine of this design it is necessary to provide a pair of combined packing and balancing disks on each side of the rotating structure each pair being provided on the opposing faces with a labyrinth or other packing to facilitate the balancing action by preventing the free escape of steam from the

high pressure to the low pressure side of the machine. If these disks are located outside of the wheels the overall length of the turbine will be relatively great. I have discovered that the overall length can be substantially decreased by making the balancing disks of such diameter that they can be fitted inside of the bore of the low pressure wheels, and also by arranging the steam chest so as to extend inside of the bore of the wheels and in telescopic relation thereto.

With the balancing disks arranged as described they are relatively small in diameter and it is difficult to obtain sufficient thrust pressure to overcome that due to the steam on the rotating elements. To overcome this I provide, on each side of the machine an additional packing in series with the first. Preferably but not necessarily, the clearance space in this packing is axial, that is to say, parallel with the shaft. The packing is also located within the bore of each low pressure wheel and is therefore in telescopic relation to it and the steam chest so that as a net result the parts are contained in a relatively small space measured axially of the machine.

The wheels are heat treated to render them very strong and tough, and if they are subjected in operation to the action of high temperature steam, such for example as that issuing from the packings, in such manner that a substantial increase of temperature results their strength will be very materially decreased. To prevent this objectionable action from taking place I provide each wheel with a guard or protective means whereby hot steam from the packing or other source is prevented from striking it. I also provide means for passing relatively low temperature steam over certain parts of the wheel for cooling it. The part of each wheel requiring this protection is in the region of its bore and the desired result is obtained by locating an annular member within the bore which is separated from the surrounding wall or surface of the bore by a relatively small clearance space through which steam flows after its temperature has been substantially reduced by performing work in the blade system. Since an axial flow packing arranged in telescopic relation with the bore has been provided for another purpose, its outer member can also be utilized as a guard thereby causing the member to perform three functions, *i. e.*, that of

a packing member, a guard and a means defining one wall of an annular equalizing chamber for the cooling steam.

In the drawing which illustrates one of the embodiments of my invention is shown an axial quarter section of a turbine.

1 indicates the inner part of a rotating element which is provided with rings of axially extending blades 2. On the similar 10 and companion element are other rings of axially extending blades 3 and as the steam flows radially outward through the blades, it causes said elements to revolve in opposite directions. Each element is mounted on a 15 stub shaft 4 which in turn is connected to a main shaft (not shown). To each inner element is attached by an expansion ring 5 an intermediate blade carrying element 6. The purpose of these expansion rings whenever 20 used is to permit the parts to expand and contract by unequal amounts without transmitting undue stresses from one to the other, and also, when used in the rotor, to transmit power. They also serve to restrict 25 the passage of heat from one part to the other and also as means to prevent the passage of steam from one region to another. Briefly, each comprises a ring, cylindrical or slightly conical, with enlarged ends 30 which are secured in sockets in the associated parts.

7 indicates the wheels which are supported by the intermediate elements through expansion rings 8 and are located on opposite 35 sides of the radial flow blade system. The wheels carry intermediate pressure axially extending blade rings 9 and 10 and also radially extending blades 11. Steam is directed against the latter blades by nozzles 40 or other fluid directing devices 12 carried by an annular holder 13 which is supported by the turbine casing 14. The wheels, on account of the heavy stresses to which they are subjected, have a very large mass of metal 45 in their central portion or hub 15, the latter having a large central bore 16.

Attached to the outer sides or faces of the high and intermediate pressure blade carrying elements are combined balancing and 50 packing disks 17. Situated opposite each revolving disk 17 is a stationary disk 18 which is supported by a steam chest 19. Between the disks is a labyrinth packing 20, shown in simplified form, to restrict the flow 55 of steam from the supply chamber 21 outwardly and in this manner maintain a steam pressure on the disks for balancing the tendency of the rotor elements to move axially due to the steam flowing through the blade 60 system. It is to be noted that the diameter of the disks 17 and 18 is less than that of the bore of the wheels and also that they are located within said bores. By this arrangement it is possible to separate the parts by 65 relative axial movement.

Owing to the relatively small diameter of the disks to that of the revolving structure, it is not practical to maintain by the labyrinth packing 20 a sufficient steam pressure on their working faces to fully balance the 70 blade carrying elements, and for that reason auxiliary axial packings are provided and arranged in series therewith. Each of these axial packings comprises an outer annular member 22 arranged in telescopic relation to the bore of the wheel and supported by an intermediate blade carrying element 75 through the expansion ring 23. The inner face of the member is provided with grooves or other baffling devices to restrict the flow 80 of steam. Inside the member is a second annular member 24 having suitable projections or other devices co-operating with the grooves in the outer member to reduce leakage. The member 24 is supported by the 85 stationary balancing disk 18 and steam chest through the expansion ring 25. The radial and axial packings acting together maintain a sufficient steam pressure on the opposed faces of disks 17 and 18 to balance 90 the end thrust on the rotating elements.

The steam chest 19 is supported by the turbine casing or some part thereof, there being an expansion ring 26 between the two. The inner end of the chest supports the 95 balancing disk 18 by any suitable means, as for example by expansion rings.

It will be observed that the axial flow packings as well as the steam chests are in telescopic relation to the wheels 7 and by 100 reason of this fact it will be seen that the machine as a whole can be made relatively short for a given output.

Steam is admitted to the chamber 21 in the chest by the conduit 27. Surrounding 105 said chamber is a second chamber 28 through which steam for overload purposes is admitted by passages 29 and 30 to an intermediate region of the rotating elements. The supply conduit for this chamber has 110 been omitted for simplicity. 31 indicates a shaft packing and 32 a portion of a conduit which receives steam therefrom and conveys it to some suitable place, as for example to a feed water heater. 115

As before stated, the wheels are heat treated and to protect them from the effects of high temperature steam in the region of the bore, a guard is provided. Since an annular packing member is provided for another reason, I make use of it for this purpose. To this end the peripheral surface of the member is turned true and is separated from the wall of the bore by a clearance space 33. To permit the flow of cooling 120 steam through the clearance, the expansion ring 8 is provided with one or more small holes or passages 34 through which steam flows after it has done work in the radial flow blade system and has had its tempera- 125

ture substantially reduced. It is evident that instead of making passages in the rotor they may be made in the intermediate portion 6 of the rotor. It will be observed that 5 the inner end of the member 22 also defines one wall of an annular steam chamber 35, which assures a uniform flow of steam through the clearance space, the other walls of the chamber being defined by the expansion ring 8 and associated parts of the rotor. The steam leaving the clearance mixes with the exhaust from the low pressure blades 11 and passes to the condenser or other exhaust.

In operation steam flows through the turbine 15 as indicated by the arrows and at the same time steam flows through the radial and axial flow packings. The steam flowing through the blade systems tends to separate the blade carrying elements, but this is counteracted or balanced by the steam acting on 20 the working faces of the balancing disks 17 and 18. Due to the addition of the axial flow packings, sufficient pressure will be exerted on said disks at all times for this 25 purpose and mechanical contact or rubbing of the parts is avoided.

In accordance with the provisions of the patent statutes, I have described the principle of operation of my invention, together 30 with the apparatus which I now consider to represent the best embodiment thereof; but I desire to have it understood that the apparatus shown is only illustrative and that the invention can be carried out by other 35 means.

What I claim as new and desire to secure by Letters Patent of the United States is:—

1. In an elastic fluid turbine, the combination 40 of a pair of oppositely rotating blade carrying elements in which the low pressure portion of each is situated at one side of the high pressure portion and has an enlarged bore, a pair of balancing disks for each element which are smaller in diameter 45 than the bore of the surrounding low pressure portion, an axial packing arranged in telescopic relation with said bore, and a steam chest also arranged in telescopic relation to said bore which supplies steam to 50 the blades.

2. In an elastic fluid turbine, the combination 55 of a pair of oppositely rotating blade carrying elements in which the low pressure portion of each is situated at one side of the high pressure portion and has an enlarged bore, a pair of balancing disks for each element which are smaller in diameter than the bore of the surrounding low pressure portion, an axial packing arranged in telescopic relation with said bore and acting on 60 the steam issuing from between the disks, and a steam chest arranged in telescopic relation with said bore and also the axial packing.

3. In an elastic fluid turbine, the combina-

tion of a pair of oppositely rotating blade carrying elements in which the low pressure portion of each is situated at one side of the high pressure portion and has an enlarged bore, a chest which supplies steam to the 70 blades and is in telescopic relation to the bore of said low pressure element, a pair of balancing disks, one of which is secured to a rotating element, the other being secured to the inner end of the steam chest, and an axial packing which receives steam from between the disks and restricts its flow and is in telescopic relation with said bore.

4. In an elastic fluid turbine, the combination 80 of a pair of oppositely rotating blade carrying elements in which the low pressure portion of each is situated at one side of the high pressure portion and has an enlarged bore, a chest which supplies steam to the blades and is in telescopic relation to the 85 bore of said low pressure element, a pair of balancing disks, one of which is secured to a rotating element, the other being secured to the inner end of the steam chest, and an axial packing which receives steam from between the disks and restricts its flow, said 90 packing comprising two cylindrical members in telescopic relation to said bore, one of said members being carried by the rotor and the other by one of the balancing disks. 95

5. In an elastic fluid turbine, the combination 100 of a pair of oppositely rotating blade carrying elements in which the low pressure portion of each is situated at one side of the high pressure portion has an enlarged bore, steam chests on opposite sides of the elements which are in telescopic relation to said bores, a pair of balancing disks between each element and the chest on that side, one of said disks being carried by an element and 105 the other by the chest, and axial packing for each side of the machine arranged in telescopic relation to the surrounding bore of the low pressure portion, said packing receiving steam from the adjacent pair of 110 disks and restricting its flow toward the point of exhaust.

6. In an elastic fluid turbine, the combination 115 of oppositely rotating blade carrying elements, a bladed wheel associated with each element and rotating therewith which has an enlarged bore, a pair of balancing disks for each element located within the bore of its wheel, and an annular guard rotating with the blades which is located between the periphery of each pair of disks and the bore of the surrounding wheel. 120

7. In an elastic fluid turbine, the combination 125 of oppositely rotating blade carrying elements, a bladed wheel associated with each element and rotating therewith which has an enlarged bore, a pair of balancing disks for each element located within the bore of its wheel, an annular guard rotating with the blades which is located between the 130

periphery of the disks and the bore of the surrounding wheel, there being a space between them, and means for supplying steam to each space for cooling the wheel after it 5 has had its temperature reduced by performing work in some of the blades.

8. In an elastic fluid turbine, the combination of oppositely rotating blade carrying elements, a bladed wheel for each element 10 having an enlarged bore, an expansion ring which connects each wheel with its element and is provided with a steam passage, a pair of balancing disks for each element located within the bore of its associated wheel, an 15 annular guard which extends through the bore of each wheel and is attached to an element, said guard defining one wall of a clearance space and chamber of which the expansion ring and associated parts form 20 the other end and through which steam flows from the passage in the expansion ring to the clearance.

9. In an elastic fluid turbine, the combination of oppositely rotating blade carrying 25 elements, a bladed wheel connected to each element which has an enlarged bore, a pair of balancing disks for each element located within the bore of its wheel, an axial packing also located within each bore and receiving 30 steam from between the disks, which comprises an inner and an outer member, said outer member being separated from the bore by a clearance space and also forming a guard, and means for admitting steam at 35 reduced temperature to the clearance space for cooling the wheel.

10. In an elastic fluid turbine, the combination of a rotor, axially extending blade rings carried thereby, a bladed wheel having 40 an enlarged bore, said wheel being located at one side of said rotor, an expansion ring which connects the wheel to the rotor, a pair of balancing disks located within the bore of said wheel, one of said disks being connected 45 to said rotor to turn therewith and the other being stationary, and packing means between said disks.

11. In an elastic fluid turbine, the combination of a pair of oppositely rotating blade 50 carrying elements in which the low pressure

portion of each is situated at one side of the high pressure portion and has an enlarged bore, a pair of balancing disks for each element which are smaller in diameter than the bore of the surrounding low pressure portion, and an elastic fluid chest arranged in telescopic relation to said bore which supplies 55 elastic fluid to the blades.

12. In an elastic fluid turbine, the combination of a pair of oppositely rotating blade carrying elements in which the low pressure portion of each is situated at one side of the high pressure portion and has an enlarged bore, a chest which supplies elastic fluid to the blades and is in telescopic relation to the 60 bore of said low pressure portion and a pair of balancing disks one of which is secured to a rotating element, the other being secured to the inner end of the elastic fluid chest.

13. In an elastic fluid turbine, the combination of a pair of oppositely rotating blade-carrying elements in which the low pressure portion of each is situated at one side of the high pressure portion and has an 65 enlarged bore, a chest which supplies elastic fluid to the blades and is in telescopic relation to the bore of said low pressure portion, a pair of balancing disks one of which is secured to a rotating element, the other being secured to the inner end of the elastic fluid chest, and an additional packing which receives elastic fluid from between the disks and restricts its flow.

14. In an elastic fluid turbine, the combination of a rotor having axially extending blade rings, a bladed wheel located at one side of said rotor and having an enlarged bore, an expansion ring connecting said wheel to said rotor, an elastic fluid chest in 90 telescopic relation to said bore, for supplying elastic fluid to the rotor, and balancing disks also in telescopic relation to said bore, one of said disks being connected to the rotor and the other to said elastic fluid 95 chest.

In witness whereof I have hereunto set my hand this 5th day of February, 1919.

FREDRIK LJUNGSTRÖM.
